UNITED STATES PATENT OFFICE.

WILLIAM E. HOWLETT, OF MOLINE, ILLINOIS.

AUTOMATIC SELF-LOADING HOIST.

Application filed March 5, 1925. Serial No. 13,118.

The invention relates to an automatic self-loading hoist.

It relates particularly to an automatic hoist for elevating coal at coaling stations 5 on railroads but it may be used for any other suitable purpose.

An automatic hoist for this purpose usually includes an elevating tower having a coal bin near its base feeding by gravity 10 into the tower near the bottom of the tower well. An electric or power driven hoist which automatically reverses itself serves to raise and lower a hoisting bucket in the tower. The bucket is allowed to pause long 15 enough at the bottom of the tower to be loaded and long enough at the top to be dumped. The opening from the coal bin in- to the tower is closed as the bucket is raised to prevent the coal from passing into the 20 tower well and it is opened when the bucket is lowered to permit the bucket to be filled.

One of the difficult problems in a hoist of this type which has not been successfully and economically solved heretofore is the 25 proper loading of the bucket and the closing of the opening from the bin without spilling coal or other material into the tower well, either at the time of loading, in the closing of the door, or in the raising of the 30 bucket. The present invention is directed to a solution of this problem.

The general object of the invention is to provide an improved automatic self-loading hoist.

35 A more particular object is to provide a simplified automatic hoist constructed so that the hoisting bucket will be loaded and the opening from the source of material supply closed without spilling or dribbling 40 any of the material into the tower well.

Another object is to unload a portion of the material to be hoisted during the initial raising movement of the hoisting bucket.

45 A further object is to provide an improved bucket construction in an automatic hoist of this type.

Other objects and advantages of the invention will hereinafter appear.

50 An embodiment of the invention is illustrated in the accompanying drawings in which—

Figure 1 is a side elevation of a portion of the hoisting tower showing the hoisting 55 bucket in lowered position.

Figure 2 is a view similar to Figure 1

showing the hoisting bucket after it has been raised a short distance.

Figure 3 is a view similar to Figure 1 after the hoisting bucket has been raised still 60 higher.

Figure 4 is a side elevation of the portion of the bucket mechanism showing it in three different positions.

Figure 5 is a back elevation showing the 65 general arrangement of the hoisting bucket, an electric hoist and a door for closing the receptacle containing the material to be hoisted.

Figure 6 is a rear elevation showing the 70 bucket in lowered position.

Figure 7 is a front elevation of the hoisting bucket.

Figure 8 is a detail side elevation of one 75 of the cam roller arms showing how it is connected to its shaft.

Figure 9 is an end elevation of the arm shown in Fig. 8.

Fig. 10 is a detail view of the device for causing the bucket to tilt after it has been 80 hoisted.

The general features of the hoist are a tower 1 provided with a bin or receptacle 2 for receiving material to be hoisted, a door or closure 3 for closing the opening 85 from the bin into the tower, and a hoisting bucket 4 which is raised and lowered within the tower by means of an electric hoist 5 controlled by automatic switches on the switchboard 6. 90

The tower 1 is usually rectangular and it varies in height according to the requirements of the particular installation. It is preferably built of concrete and steel. It forms a passage way or well in which the 95 hoisting bucket is raised up and down. A concrete or wood base or block 7 at the bottom of the tower well forms a seat for the hoisting bucket when it is lowered.

The bin or receptacle 2 is located near 100 the bottom of the tower and it preferably has a sloping bottom 8 so that the material to be hoisted will feed by gravity through the opening in the tower into the hoisting bucket. In the embodiment of the invention 105 illustrated, the bin is built integral with the tower but it may be independent if desired. The opening 9 leading from the bin into the tower is made relatively large and an adjustable choker plate 10 is located forward 110 of the opening, said plate being adjustably bolted to angle bars 11. The height of the

plate can be varied to properly regulate the flow of materials having different angles of repose. The location of the plate ahead of the opening leaves a vacant space at the forward part of the bin into which excess material from the hoisting bucket may be thrown.

The door or closure 3 is a heavy steel plate the sides of which travel in guideways 10 in the tower which hold it against being forced outwardly by the pressure of the material in the bin. The door is heavily counterweighted by the weights 12 shown in Figure 5, which are connected to the door by 15 cables 13, passing over pulleys 14. The upward movement of the door is limited by stops 15 which prevent it from being moved by the counterweights past the opening. Its uppermost position is illustrated in Figures 20 3 and 5 in which it is shown as forming a barrier for preventing the material in the bin from flowing into the tower.

The bucket 4 is of rectangular shape with the top larger than the bottom. The width 25 of the bottom may be varied to vary the capacity of the bucket. The two sides 20 and the rear 21 are higher than the front side 22. The material to be hoisted is loaded into the bucket over the front side and 30 the height of the rear and of the two sides prevents it from falling into the tower well. The bucket is lifted by means of a heavy bail 23 pivoted at the points 24 and 25 and connected by a cable 26 passing over pulleys 27 35 to the electric hoist 5.

The electric hoist is controlled by an automatic switchboard which reverses the motor when the bucket gets to the end of its travel at the top and at the bottom of the tower. 40 Anyone of a number of well known control mechanisms can be used which will automatically raise and lower the bucket and allow it to pause long enough at the bottom to be loaded and at the top long enough to be 45 dumped.

The bucket is provided with trunnions 28 which engage sockets 29 near the top of the tower so that further upward movement of the bucket near the top of the tower dumps 50 the bucket and discharges its load. The location of these trunnions may be varied to cause the bucket to be dumped to the front or the rear. Any other suitable construction for dumping the bucket may be employed as the details of the dumping mechanism are not important in this application.

The bucket 4 carries arms 30 which engage 60 the projecting ledge 31 on the door 3, said ledge being formed by an angle iron bolted to the door. As the bucket descends, the arms 30 strike the ledge and lower the door 3. The counterweight is such that the weight of the empty bucket will lower the door. It is made as heavy as possible, however, in order that it may assist in raising

the bucket during the first part of the raising movement, and at a time when the hoisting motor is required to assert its greatest torque. The counterweight is almost heavy enough to raise the empty hoisting bucket 70 and, consequently, the hoisting motor has to raise only the weight of the material to be hoisted plus the amount by which the bucket overbalances the counterweight. In other words, the counterweight relieves the 75 hoisting motor of having to start the entire load upward.

The ledge 31 on the door is located so that when the bucket is lowered to its position on the block 7, the top of the door is just below 80 the sloping bottom of the bin 2. The position of the parts is illustrated in Figure 1.

When the bucket is raised from the position of Figure 1, the door 3 follows it and forms a barrier preventing the material in 85 the bin from sliding into the tower. As the bucket rises, the material at the top of the bucket tends to fall across the front edge of the bucket and, if no provision were made to take care of it, it would fall into the tower 90 well and continue to dribble off as the bucket continued to rise.

As previously mentioned, there is a vacant space in the bin at its front and just back of the choker plate 10. The material that first 95 falls into this space is illustrated in Figure 2 which shows the material passing from the top of the bucket over its front edge and into the space where it is prevented from dropping into a pit by the top edge of the 100 door which follows the bucket upward. In this way, the excess load in the bucket falls back into the bin and is ready to be discharged into the empty bucket when it again descends for a load. The fact that the upward movement of the door 3 is limited by its contact with the bucket insures that there will always be an opening into the bin above the door through which the excess material 105 may be dropped or discharged.

The major portion of the loose material at the top of the bucket will fall over the front edge of the bucket by gravity during the first part of the raising movement but very often small portions of it will be held 110 against falling for various reasons such as the size and arrangement of the lumps, the dampness of the material, etc. Although these small portions may not fall off initially, the jar incident to raising the bucket to the 115 top of the tower will tend to cause them to dribble off in small amounts and fall to the bottom of the tower well. This is highly undesirable and means have been provided to prevent it. The means illustrated 120 is a guard or side extension consisting of a plate 32 pivoted at the front edge of the bucket at the points 33 and 34. This plate has arms 35 carrying cam rollers adapted 125 to engage in the cam races 37 on the sides of 130

the tower. The weight of the guard and associated parts tends to normally hold it in its lower position shown in Figure 1. Springs 38 are also provided for further insuring that the parts will normally remain in this position. As the bucket is raised, the cam rollers 36 enter the cam races 37 and the guard plate is swung counterclockwise from the position shown at the bottom of Figure 4 through the center position to the position shown at the top of Figure 4. During this movement the springs 38 pass over center so that, when the guard has reached the position illustrated at the top of Figure 4, the springs hold it in this position. During this movement of the guard three things have taken place. First, as the plate is swung upwardly it throws some of the material out and back into the bin. The position of the cam races is such that the plate is swung up before the top of the bucket passes the opening above the door 3 and, consequently, any material thrown out by the plate goes back into the bin. Second, as the guard plate is swung to a vertical position an empty space is created behind the plate into which may fall any portions of the material that might tend to drop off. Third, the swinging of the plate to vertical position increases the height of the front side of the bucket thereby providing a higher barrier for preventing material from dribbling or falling off the bucket.

With this construction and association of parts, the bucket may be loaded cleanly and the material prevented from falling or dribbling off after it is loaded. All excess material is thrown back into the bin before the bucket has raised to any great height and any further material that might tend to dribble off is prevented from falling by a guard plate.

The operation of the hoist is, briefly, as follows:

As the bucket is lowered it strikes the door 3, forces it downward, raises the counterweights, and material flows from the bin into the bucket over its front side. The material flows into the bucket until it has reached its normal angle of repose shown, for example, in Figure 1. The electric switching mechanism is timed so as to allow the bucket to remain at the bottom of the tower sufficiently long to be filled. The switching device then reverses the motor which starts to raise the bucket. The heavily counterweighted door aids in raising some of the weight of the bucket as it starts on its upward movement. As the bucket moves upward, the door 3 follows it closely and forms a barrier to prevent the material in the bin from flowing into the tower. The extra material at the top of the bucket moves further upward, the cam rollers enter the

cam races 37 and swing the guard 32 counterclockwise thereby throwing a small quantity of material back into the bin. This creates a space at the front edge of the bucket to prevent any further material from falling off. The hoisting continues until the bucket reaches to top of the tower where it is automatically dumped. The control switches for the hoisting motor allow the bucket to hesitate long enough to be emptied after which the motor is reversed and the bucket is lowered. As the bucket is lowered the cam rollers 36 again enter the races 37 but the resulting movement in this case is in the reverse direction thereby returning the guard plate to its lowered position as illustrated in Figure 1.

In this way, the hoist operates automatically and loads itself. Coal or other material may be hoisted from bins near the ground to bins at the top of a tower from where it may be discharged to the coal tenders of locomotives, to storage bins, or elsewhere.

In the event that some accident should happen to the apparatus so that the hoisting bucket would drop before it reached the top of the tower, the cam rollers would enter the cam slots 37 to reverse the position of the guard plate 32. If this happened there might be considerable material behind the plate so that it could not be swung to its lowered position with the result that something would have to break. To provide against such a contingency, shear pins 40 shown in detail in Figures 8 and 9 are used for fastening the arms to the shaft carrying the guard plate 32. When an excessive strain is put on the arms as it would be in the case above-described, the pins will break. The arms may then move relative to the shaft without injury to the mechanism. These pins can be easily replaced.

It is to be understood that the construction shown is for the purpose of illustration only and that variations may be made in it without departing from the spirit and scope of the invention as defined in the appended claims.

What I claim is:

1. An automatic, self-loading hoist having a receptacle provided with an opening through which material to be hoisted may pass, a closure for said opening, a hoisting bucket, means for automatically lowering and raising said bucket to and from said opening, means for opening said closure when the bucket is lowered to permit the bucket to be filled, and automatic means for preventing material from dribbling from said bucket after it has been raised a predetermined height.

2. An automatic, self-loading hoist having a receptacle provided with an opening through which material to be hoisted may

pass, a closure for said opening, a hoisting bucket, means for automatically lowering and raising said bucket to and from said opening, means for opening the closure when the bucket is lowered to permit the bucket to be filled, and means carried by said bucket and operated automatically during the raising movement thereof to prevent material from dribbling from said bucket.

bucket to and from said opening, said bucket being positioned so that, when lowered, it is filled from said opening over its front side, means for opening the closure when the bucket is lowered to permit the bucket to be filled, and means carried by said bucket and operated automatically by the raising thereof for increasing the height of the front of the bucket during the raising movement thereof. 70 75

10 3. An automatic, self-loading hoist having
a receptacle provided with an opening
through which material to be hoisted may
pass, a closure for said opening, a hoisting
bucket, means for automatically lowering
15 and raising said bucket to and from said
opening, means for opening said closure
when the bucket is lowered to permit the
bucket to be filled, and means for automatically
unloading a portion of the material in
20 the bucket during the initial raising move-
ment thereof.

8. An automatic self-loading hoist having

4. An automatic, self-loading hoist having a receptacle provided with an opening through which material to be hoisted may pass, a closure for said opening, a hoisting bucket, means for automatically lowering and raising said bucket to and from said opening, means for opening said closure when the bucket is lowered to permit the bucket to be filled, and means for automatically returning a portion of the material in said bucket to said receptacle during the initial raising movement of the bucket.

8. An automatic, self-loading hoist having a receptacle provided with an opening through which material to be hoisted may pass, a closure normally biased to close said opening, a hoisting bucket having its sides and rear relatively high and its front relatively low, means for automatically lowering and raising said bucket to and from said opening, said bucket being positioned so that, when lowered, it is filled from said opening over its front side, means for causing the lowering of the bucket to open said closure, said opening and bucket being associated so that, as the bucket is raised, loose material not held in by the front of the bucket will be returned to said receptacle, and means carried by said bucket and operated automatically as the bucket is raised for preventing material from falling over the front side of said bucket. 111

5. An automatic, self-loading hoist having a receptacle provided with an opening through which material to be hoisted may pass, a closure for said opening, a hoisting bucket, means for automatically lowering and raising said bucket to and from said opening, means for opening said closure when the bucket is lowered to permit the bucket to be filled, and means for automatically increasing the height of one side of the bucket during the raising movement thereof.

9. An automatic, self-loading hoist having a receptacle provided with an opening through which material to be hoisted may pass, a sliding closure normally biased upward to close said opening, a hoisting bucket having its sides and rear relatively high and its front relatively low, means for automatically lowering and raising said bucket to and from said opening, said bucket being positioned so that, when lowered, it is filled from said opening over its front side, means carried by the bucket for carrying the door downward as the bucket is lowered to thereby open said closure to permit the bucket to be filled, said opening and bucket being associated so that, as the bucket is raised, the loose material not held in by the front side of the bucket will be returned to the receptacle, and means carried by said bucket and operated automatically as the bucket is raised to increase the height of the front side of the bucket to permit further loose material from falling out. 100
105
110
115

45 6. An automatic, self-loading hoist having
a receptacle provided with an opening
through which material to be hoisted may
pass, a closure for said opening, a hoisting
bucket, means for automatically lowering
50 and raising said bucket to and from said
opening, means for opening said closure
when the bucket is lowered to permit the
bucket to be filled, and means for automatically
returning a portion of the material in
55 said bucket to said receptacle and for in-
creasing the height of the loading side of
said bucket during the initial raising move-
ment thereof.

10. An automatic, self-loading hoist having a receptacle provided with an opening 120 through which material to be hoisted may pass, a closure for said opening, a hoisting bucket, means for automatically lowering said bucket to and raising it from said opening, and means for moving the closure to 125 closed position as the bucket is raised, said opening having an upward branch extending in the direction of travel of the bucket above the position of the closure when in closed position and adjacent the path of the 130

63 7. An automatic, self-loading hoist having
a receptacle provided with an opening
through which material to be hoisted may
pass, a closure for said opening, a hoisting
bucket having its sides and rear relatively
high and its front relatively low, means for
65 automatically lowering and raising said

- loading side of the bucket for catching loose material from the loading side of said bucket as it is raised.
11. An automatic, self-loading hoist having a receptacle provided with an opening through which material to be hoisted may pass, a closure for said opening, a hoisting bucket, a tower in which said bucket may be raised and lowered, means for automatically lowering said bucket to and raising it from said opening, and means for moving the closure to closed position as the bucket is raised, the wall in said tower above said opening being spaced from the path of said bucket to provide a passage for permitting loose material from the loading side of said bucket to fall into the receptacle opening as the bucket rises.
12. An automatic, self-loading hoist having a receptacle provided with an opening through which material to be hoisted may pass, a closure for said opening, a choker plate in said opening spaced from said closure to regulate the flow of material and to provide a space between the plate and the closure, a hoisting bucket, means for automatically lowering said bucket to and raising it from said opening, and means of moving the closure to closed position as the bucket is raised, said opening between the choker plate and the closure extending upwardly in the direction of travel of the bucket so that when the closure is in closed position loose material from the loading side of the bucket will fall into said receptacle opening as the bucket rises.
13. An automatic, self-loading hoist having a tower, a bin near the bottom of the tower provided with a sloping bottom and an opening into said tower through which material to be hoisted will flow by gravity, a door normally biased upwardly to form a barrier preventing material from flowing through said opening, a choker plate in said opening for regulating the flow of material and for forming a space between the plate and the closure, a hoisting bucket having its two sides and rear higher than its front side, means for automatically raising said bucket and for lowering it to a position such that it may be filled over its front side from said opening, devices carried by said bucket for lowering said door as the bucket is lowered, said bucket being located relative to the receptacle and closure so that, as the bucket is raised, the loose material not held in by the front side of the bucket will fall into the space between the choker plate and the closure, and means carried by the bucket and operating automatically to throw a portion of the material in said bucket into said space and to increase the height of the front side of the bucket.
14. An automatic, self-loading hoist having a receptacle provided with an opening
- through which material to be hoisted may pass, a closure for said opening, a hoisting bucket, means for automatically lowering and raising said bucket to and from said opening, means for opening said closure as the bucket is lowered to permit the bucket to be filled with material flowing through said opening, a guard plate pivoted to the front of the bucket, and cam means for swinging said plate upwardly to increase the height of the front side of the bucket as it is raised and for swinging said plate downwardly as the bucket is lowered.
15. A bucket for automatic, self-loading hoists having relatively high sides and rear and a relatively low front over which the bucket can be filled, an extension for the front side of said bucket, and means connected to said extension adapted to be automatically operated by the raising of the bucket for moving said extension to increase the height of the front side of the bucket.
16. A bucket for automatic, self-loading hoists having relatively high sides and rear and a relatively low front over which the bucket may be loaded, a pivoted extension for the front side normally occupying a lowered position, and means connected to said extension adapted to be automatically operated by the raising of the bucket to swing the extension upwardly to increase the height of the front side of the bucket.
17. An automatic, self-loading hoist having a receptacle provided with an opening through which material to be hoisted may pass, a closure for said opening, a hoisting bucket, means for automatically lowering and raising said bucket to and from said opening, a movable plate carried by said bucket adjacent the loading side thereof, and means for automatically moving said plate to a position to form an extension on the loading side of said bucket as the bucket is raised.
18. An automatic, self-loading hoist having a receptacle provided with an opening through which material to be hoisted may pass, a closure for said opening, a hoisting bucket, means for automatically lowering and raising said bucket to and from said opening, a movable plate carried by said bucket adjacent the loading side thereof, and means for automatically moving said plate to a position to form an extension of the loading side of the bucket as the bucket is raised, said plate being positioned so that said movement causes the plate to discharge a portion of the material in the bucket into the receptacle.
19. The combination in an automatic self-loading hoist of a receptacle having an opening through which material to be hoisted may pass, a closure for said opening, means for moving the closure to closed position, a hoisting bucket, means for au-

tomatically lowering and raising said bucket to and from said opening, means for automatically opening said closure when the bucket is lowered to thereby permit the material to flow into said bucket, and means carried by the bucket and operated automatically after the edge of the loading side of the bucket has passed the level of the material in the opening for returning to 10 said receptacle a portion of the material near the loading side of the bucket.

20. The combination in an automatic, self-loading hoist of a receptacle having an opening through which material to be hoisted may pass, a closure for said opening, a hoisting bucket, means for automatically lowering and raising said bucket to and from said opening, and a plate pivoted to the loading side of said bucket and normally 15 extending inside thereof, said plate being provided with means which is set into operation by the raising of the bucket for turning said plate to a vertical position to increase the height of the loading side of 20 said bucket and discharge material in front of the plate from the bucket.

21. The combination in an automatic, self-loading hoist of a receptacle having an opening through which material to be hoisted may pass, a closure for said opening, a hoisting bucket, means for automatically 25

lowering and raising said bucket to and from said opening, a plate pivoted adjacent the loading side of said bucket and normally extending inside thereof, said plate having 30 operating members connected therewith, and actuating devices in the path of said members for engaging them as the bucket is raised to turn said plate to vertical position, said devices also engaging said members as the bucket is lowered to return the plate to its position inside the bucket.

22. An automatic, self-loading hoist having a receptacle provided with an opening through which material to be hoisted may 35 pass, a closure for said opening, a hoisting bucket, means for automatically lowering and raising said bucket to and from said opening, a plate pivoted adjacent the loading side of said bucket and normally extending 40 inside the bucket, and actuating devices for automatically turning said plate to a vertical position as the bucket is raised and for returning said plate to its position inside the bucket as the bucket is lowered, said 45 actuating devices including portions which yield in the event said bucket is lowered when said plate cannot be turned to the inside of said bucket.

In testimony whereof, I affix my signature.

WILLIAM E. HOWLETT.
